F. DUTCHER.
RAILWAY SIGNAL TORPEDO.
APPLICATION FILED OCT. 18, 1918.

1,296,493.

Patented Mar. 4, 1919.

Frank Glutcher, Inventor
A. S. Pattison, Attorney

UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,296,493.

Specification of Letters Patent.

Patented Mar. 4, 1919.

Application filed October 18, 1918. Serial No. 258,715.

To all whom it may concern:

Be it known that I, FRANK DUTCHER, a citizen of the United States, residing at Versailles, in the county of Allegheny and 5 State of Pennsylvania, have invented certain new and useful Improvements in Railway Signal-Torpedoes, of which the following is a specification, reference being had therein to the accompanying drawing.

10 This invention relates to improvements in railway signal torpedoes, and pertains to that type of torpedo which has become known to the trade as "paper" or "non-flying."

15 The object of the present improvement is to provide a novel way of attaching the rail-engaging strap to the torpedo, and a novel way of preventing the strap from having a longitudinal or end-wise movement 20 in respect to the torpedo case.

In the accompanying drawing—

Figure 1 is an enlarged inverted perspective view of a railway torpedo with my improvement applied thereto.

25 Fig. 2 is a vertical transverse sectional view of the invention.

Fig. 3 is a detached perspective view of the ring which forms the side wall of the case and the rail-attaching member.

30 Fig. 4 is a perspective view of the ring which forms the side wall of the case, showing a modified construction of the manner of attaching the rail-engaging member.

Fig. 5 is a detached perspective view of 35 the rail-attaching member shown in Fig. 4.

In carrying out my present improvement, I prefer to use a circular flat form of torpedo case, though the shape of the torpedo may be varied without departing from the 40 spirit and scope of the present improvement.

In fact, the case may be rectangular in plan view, or any other shape to which the improvement is adapted.

The case here shown, comprises a fibrous 45 or paper ring 1, a fibrous or paper disk 2 forming the top of the case, a fibrous or paper disk 3 forming the bottom of the explosive-carrying case, and below the disk 3 is a third disk 4, all the disks being made 50 of fiber or paper.

The ring and disks are preferably water-proof in any suitable manner and the explosive 5 is between the disks 2 and 3. This explosive is preferably of the tablet form.

The ring 1 is provided with a narrow peripheral bur or flange 6 at each edge, and these flanges serve to support the disks within the ring 1. Thus far I have described a construction of torpedo which is disclosed and claimed in my co-pending application, filed 55 October 18th 1918, Serial No. 258,714, and, therefore, no claim is made in this application to the construction of the torpedo case *per se*, as that is the subject-matter of the above numbered co-pending application. 60 65

In my present improvement the rail-engaging member 7 passes through suitably-shaped openings 8 in the ring 1, and between the disks 3 and 4. To make the joints between the peripheries of the disks 2 and 4 70 and the ring water-proof, I place a suitable quantity of water-proof cement 9 at that point, which also serves to assist the flanges 6 in holding the disks within the ring.

As here shown, the openings 8 are in the 75 form of notches made in the lower edge of the ring 1, though other forms of openings may be made, through which the strap or rail-engaging member 7 passes and still be within the generic invention here disclosed.

For the purpose of preventing the rail-engaging member or strap 7 from being pulled longitudinally through the case, I provide the member 7 with shoulders adapted 80 to engage or interlock or abut against the ring 1 and prevent the longitudinal movement of the strap or member 7.

In Figs. 1, 2 and 3, I show one form of shoulder to abut against the ring, which is 85 formed by depressing the member 7, just inside of the ring, thus forming shoulders 10 which will abut against the ring and prevent the longitudinal movement thereof, as will be readily understood.

In Figs. 4 and 5, I show a modification in the manner of forming shoulders on the member or strap 7, which consists in providing the strap or member with notches 11, and making the notches 8^a narrower than 100 the member 7, so that the notches interlock with the ring and will abut thereagainst to prevent the strap from having a longitudinal movement.

While I have shown the shoulders 10 located within the side wall or ring 1 of the case, and preferably so located, it will be understood that the shoulders can be formed

outside of the ring and perform the same function of preventing longitudinal movement of the strap or member 7.

Having thus described my invention, what I claim and desire to secure by Letters Patent is:

1. An improved railway signal torpedo, comprising an explosive containing case, and a rail-engaging member passing below the bottom of the case and through the side wall of the case.
2. An improved railway signal torpedo comprising an explosive containing case, a strap passing through the side wall of the case and below the bottom and connected thereto, the rail-engaging member having shoulders adapted to abut against the side wall of the case to prevent longitudinal movement of the rail-engaging member.
3. An improved railway signal torpedo, comprising an explosive containing case, the side wall of the case having oppositely arranged openings below the bottom of the explosive containing case, a rail-engaging member passing through the openings and connected with the said bottom.
4. An improved railway signal torpedo comprising an explosive containing case, the side wall of the case having oppositely arranged notches below its bottom, a rail-engaging member passing through the notches and against the bottom, and a member below the bottom and rail-engaging member and serving to connect the rail-engaging member to the said bottom.
5. An improved railway signal torpedo comprising an explosive containing case, having oppositely arranged openings below the bottom, a rail-engaging member passing through the openings and against the bottom and another disk below the rail-engaging member and forming a double wall bottom for connecting the rail-engaging member thereto.
6. An improved railway signal torpedo, comprising a case having a double wall bot-

tom, of a rail-engaging member passing through the side wall of the case and between the walls of the bottom.

7. An improved railway signal torpedo comprising a case having a double wall bottom, of a rail-engaging member passing through the side wall of the case, between the walls of the bottom, and having shoulders adapted to engage the side wall of the case to prevent the longitudinal movement of the rail-engaging member.

8. An improved railway signal torpedo comprising an explosive containing case, a side wall of the case having oppositely arranged notches, a rail-engaging strap passing through the notches and against the bottom, means for holding the rail-engaging member against the said bottom, the rail-engaging member having shoulders formed by depression and adapted to engage the side wall of the case to prevent longitudinal movement thereof.

9. An improved railway torpedo comprising an explosive containing case, composed of a ring and disks within the ring forming a bottom and a top for the case, the ring extending below the said bottom and provided with openings and a rail-engaging member passing through the openings below and attached to the said bottom.

10. An improved railway signal torpedo, comprising a case composed of a ring and two disks, one forming the top and the other the bottom of the explosive containing case, said ring projecting below the bottom and having oppositely arranged openings, a rail-engaging member passing through the opening and against the bottom, and a third disk below the rail-engaging member and serving to connect it to the said bottom.

In testimony whereof I hereunto affix my signature in the presence of two witnesses.

FRANK DUTCHER.
